UNITED STATES PATENT OFFICE

2,669,437

NONROTARY GEL FUEL HOMOGENIZER

Leon Jean Geeraert, Brooklyn, N. Y., assignor to
The Geeraert Corporation, New York, N. Y., a
corporation of New York

Application July 26, 1952, Serial No. 301,129

10 Claims. (Cl. 259—4)

1

The invention relates in general to fluid homogenizers and has for its primary object to provide a portable device of this kind which is sufficiently compact and light in weight to be practicable for military use as an integral part of a flame thrower gun in order that the lethal fuel therefor, which is a gel composed of gasoline thickened by addition of napalm, may be produced while the gun is being fired in combat to meet the needs of the moment only, since this mode of production possesses important advantages affecting the logistics of battlefield supply.

In this connection, it may be explained that in military combat operations gasoline, which constitutes about sixty per cent of the gel fuel mixture, is extensively required for consumption in the engines of motor vehicles, tanks, electrical generators, etc., and therefore is a munition of war whose supply in quantities adequate to meet all needs may be prohibited by existing combat conditions. It follows that, in a fluid combat situation, it is highly undesirable to have substantial quantities of gasoline irrecoverably diverted to the production of flame thrower fuel in advance of an attack when the exact requirements are not known and the normal tendency leans toward overproduction. Obviously, it is much more economical to commit the required gasoline to mixture with napalm in production of the gel fuel only while the latter is actually being consumed in combat firing of a flame thrower gun. Any unused gasoline is thereby saved for the general reserve supply. Moreover, whenever the flame thrower gun is carried by a self-propelled mount, such as a tank, it becomes practicable to employ a common gasoline tank with means for controlled selective feeding of gasoline to the propulsive engine and to the gun's homogenizer at will. In this way, every gallon of precious gasoline will be conserved as such until actually consumed when and where most needed.

Heretofore, this more economical mode of gel fuel production has not been feasible due to the lack of a homogenizer of suitable compactness and weight. Rotary homogenizers are prohibitively bulky and heavy, due to the inclusion of moving parts, prime mover, and power transmission means.

I achieve my primary object by providing a non-rotary homogenizer of extremely small size in which napalm and gasoline under pressure come together in high velocity streams in the emulsification process, and by combining the homogenizer with a flame thrower gun in such a manner that the firing trigger of the gun controls the flow of the above enumerated gel ingredients.

Another object of the invention is to utilize

2

the improved non-rotary homogenizer in a new homogenization process wherein the gel produced is a stable combination of colloidally dispersed napalm and gasoline, the former being the dispersed phase and the latter being the continuous phase. It is to be understood, however, that my homogenizer is not a colloid mill. The napalm enters the homogenizer in a liquefied colloidal state created theretofore elsewhere in the line of supply by a true colloid mill.

To be more explicit, the physical structure of my improved homogenizer includes means to impart high-velocity vortical motion to a stream of gasoline and simultaneously inject napalm in its liquefied colloidal state and under high pressure into the gasoline stream in the region of the so-called "vortex tube," thereby causing the colloidal particles of napalm to become dispersed uniformly in the gasoline through the influence of centrifugal force to form a stable gel emulsion suitable for the intended use.

It is also an object of the invention to provide a homogenizer structure which employs a system of spiral flow generating means including channels and baffle plates of different pitch characteristics arranged in three distinct successive zones, whereby, in the primary zone, vortical motion is initially imparted to the incoming stream of gasoline; then, in the secondary zone, the pitch of the spiral path is reduced to increase the velocity of circular motion with proportionate increase in generation of centrifugal force; and finally, in a tertiary, more extensive zone, the pitch of the spiral path is gradually increased to restore the axial velocity of the stream of fluid, which by this time has become to the gel mixture after injection of napalm in the second zone, to that required for projection of a long-range rod of lethal fuel by the flame thrower gun.

The improved homogenizer is specifically adapted to cooperate with the type of flame thrower gun disclosed in my copending patent application Serial No. 289,746, filed May 24, 1952, wherein firing of the weapon is triggered by the valve means for controlling admission of gel fuel to the gun breech, so the discharge valve of the homogenizer actually serves as the gun trigger. This means that the flow of gel fuel in the homogenizer is brought to a sudden stop every time the discharge valve is closed to cease firing. Under such conditions, the shock of sudden deceleration of velocity of the fuel stream would cause serious damage to the homogenizer structure if the pressure were not relieved in some way. It, therefore, is a further object of the invention to incorporate means for absorbing that shock safely.

Other objects, features and advantages of the invention should become apparent as the fol-

lowing specific description is read in connection with the accompanying drawings, in which:

Fig. 1 is a side elevation of a homogenizer constructed in accordance with the present invention; Fig. 2 is a longitudinal cross-sectional view of the same; and Fig. 3 is a horizontal section on line 3-3 of Fig. 2 with the discharge valve shown closed but with the direction of flow of the gel fuel when the valve is open indicated by the arrows.

Fig. 4 is a fragmentary horizontal section, on a reduced scale, through the homogenizer body in zone Y, showing the degree of stagger of the slots between baffle plate segments in adjacent baffle units to effect low pitch in the spiral path of fluid motion; and Fig. 5 is a similar view, showing the degree of baffle plate inter-segment slot stagger in zone Z to increase the pitch and consequent axial velocity of flow.

Fig. 6 is a detail fragmentary section through baffle plate segments in zones Y and Z, respectively, showing in broken lines the increase in angle of incidence which is applied to the leading edges of the segments in zone Z over that in zone Y.

Fig. 7 is a detail fragmentary cross-sectional view of one of the baffle plate segments, showing the direction of fluid flow as controlled thereby.

Fig. 8 is a longitudinal diagrammatic view of the homogenizer, showing the direction of flow of gasoline and napalm particles in the successive zones of vortical motion; Fig. 9 is a similar view in a transverse plane; and Fig. 10 is another diagrammatic view in a longitudinal plane, showing with particularity the axial trend of flow in the successive zones.

Referring now in detail to the drawings, in which like reference characters designate corresponding parts in the several views, Figs. 1 to 3, inclusive, disclose the principal structural elements of the homogenizer in its preferred form. The hollow body 30 in which the homogenizing process takes place includes a cylindrical side wall member 31 which is clamped with a fluid-tight joint between hollow end wall members 32 and 33 by tie-bolts 34. The interior of body 30 forms a vortex chamber 35 into which gasoline and liquefied napalm enter under externally applied pressure (of the order of 2500 lbs. per sq. in.) and are united in high-velocity vortical motion and from which emerges the stable gel fuel product of that action.

The "napalm" which is intended to be the dispersed phase ingredient in military use of the improved homogenizer is a special aluminum soap, or a mixture of such soaps, which was developed by and for the Chemical Warfare Service (now Chemical Corps), U. S. Army, in the preparation of thickened fuel compositions for flame throwers.

The means for imparting initial vortical motion to the entering gasoline stream includes a primary impeller 36 of inverted frusto-conical general form, which is set in a chamber 37 of matching form provided in lower end wall member 32. Impeller 36 has spiral peripheral grooves or channels 38 which lead from gasoline intake port 39 at the bottom of chamber 37 to and through the open upper face of the latter. By arbitrary choice, grooves 38 are twisted in a direction designed to impel the fluid stream clockwise throughout its helical course as indicated by the arrows in Fig. 3. Intake port 39 is connected with a gasoline supply tank (not shown).

When vortical motion is imparted to a mass of

fluid, as in this instance, a cavity or vacuum is created in the center of motion and is known technically as the "vortex tube." I have taken advantage of this phenomenon to install, along the central, vortex tube region of chamber 35 throughout a minor axial extent thereof (zone Y in Fig. 10) and immediately above impeller 36 and its grooves (zone X in Fig. 10), means for injecting the liquefied napalm ingredient into the whirling stream of gasoline. In this way, the vacuum is utilized to vaporize the injected napalm and thereby produce a momentary suspension of vapor molecules in a liquid, which is highly conducive to the initiation of colloidal dispersion of napalm in gasoline.

The napalm injection means just outlined preferably comprises a conduit formed by concentric outer and inner tubes 40 and 41, respectively. Outer tube 40 has its upper end affixed in suitable manner, as by screwthreaded engagement, with upper end wall member 33 of body 30. The lower end of tube 40 is screwthreaded into the central portion of impeller 36, whereby axial thrust on the latter by the high-velocity gasoline stream is effectively resisted. The inside diameter of tube 40 exceeds the outside diameter of tube 41 to a degree designed to provide a napalm conducting channel 42 therebetween. Top and bottom centering blocks 43 and 44, respectively, are stepped in external diameter to fit inside tubes 40 and 41 and thereby preserve the concentricity of said tubes. Block 44 serves to close the lower end of channel 42, but block 43 has peripheral channels 45 which establish intercommunication between channel 42 and napalm intake port 46, which latter is located centrally in upper end wall member 33.

Near its lower end, outer tube 40 is provided with a large number of minute radial orifices 47, which are arranged in axially spaced rows, for injection of napalm from channel 42 into chamber 35.

Spiral progress of gasoline and the gel produced following injection of napalm into the initial gasoline stream is guided and controlled in velocity and pressure from the lower end of chamber 35 to the upper end of the same (zones Y and Z in Fig. 10) by a series of annular baffle units 48 of graduated axial thickness, which are mounted in superimposed relation in a pile structure. Each baffle unit is composed of a base ring 48' and a surmounting baffle plate 48'', which latter is divided by plural radial slots 49 into segmental deflecting portions 50. Considering the direction of fluid flow through the annular channels 51 afforded between baffle plates 48 (see arrows in Figs. 3 and 7), the trailing edge of each segmental deflecting portion 50 lies in a plane perpendicular to the axis of chamber 35, whereas the leading edge thereof is upturned for the purpose of deflecting liquid in a continuous spiral course upwardly from each annular channel 51 into the next higher one. The slots 49 of the baffle plates of adjacent baffle units are staggered in position, whereby each slot of each baffle plate is masked axially by segmental deflecting portions 50 of the adjoining baffle plates both above and below. This staggering of the slots determines the pitch of each of the helical sub-streams that penetrate each baffle unit as components of the general vortical stream passing upwardly through the entire system of baffle units. In the napalm injection region (zone Y in Fig. 10), where low pitch and resulting high circular velocity of vortical, centrifugal force generating mo-

tion is desired, the arrangement of adjacent baffle plates and their slots is as shown in Fig. 4. Throughout the remaining upper portion of chamber 35 (zone Z in Fig. 10), where gradually increasing pitch is required, the degree of stagger is decreased, as shown in Fig. 5, and the angle of incidence (Fig. 7) of the deflecting portions of the successive baffle plates is proportionately increased. The increase in pitch of the spiral fluid path serves to increase the axial velocity of the gel on its way to the discharge means which will be described presently.

Those relatively few baffle units 48 which are located in the napalm injection region (zone Y in Fig. 10) are substantially equal in number and axial spacing to the parallel rows of orifices 47 in tube 40. The base rings 48' of these particular baffle units are provided with radial orifices 52 in cooperative registration with the respective orifices 47 to extend communication of the latter into inter-baffle plate channels 51.

It will be observed in Figs. 1 to 3, inclusive, that upper end wall member 33 of body 30 has a gel discharge port 53 controlled by valve means 54, which preferably includes a valve stem 55 mounted for tangential reciprocation in valve body 56 and having a valve plug 57 engageable with seat 58 in closed position under the influence of valve-closing spring 59. Trigger 60 of the flame thrower gun with which the homogenizer is to be integrally associated is attached to valve stem 55 and projects exteriorly from valve body 56 for manipulation in firing the flame thrower gun. As has already been explained, the gun is triggered by the opening of the discharge valve of the homogenizer, i. e. valve 54. Gel supply pipe 61 is coupled to discharge port 53 and serves to supply gel fuel to the gun breech of the flame thrower (not shown).

The opening and closing of discharge valve 54 also serves to start and stop admission of gasoline and napalm to the vortex chamber 35 of the homogenizer.

Napalm is supplied to intake port 46 through supply pipe 62. An orifice 63 controlled by adjustable needle-valve 64 connects napalm intake port 46 with channels 45 in centering block 43. Needle-valve 64 thus serves to regulate the rate of admission of napalm and may be used to establish the volumetric ratio of napalm to gasoline in the gel mixture, which usually is about 40 percent napalm to 60 percent gasoline.

Pressure gauges 65 and 66 are fitted to end wall members 32 and 33, respectively, in communication with gasoline intake port 39 and napalm intake port 46, to afford visual indication of the pressure condition at all times.

When trigger-operated gel discharge valve 54 is closed suddenly to cease firing, the high momentum of the fluid stream is checked so abruptly that damage to the homogenizer structure would be certain to occur if pressure relief and shock-absorbing means were not provided. Therefore, pressure relief and shock-absorbing means have been added to vortex chamber 35 in close proximity to each of the intake ports 39 and 46.

Adjacent to gasoline intake port 39, a lateral boss 67 is formed on lower end wall member 32. This boss has a cylindrical chamber 68 opening through its outer face and a reduced concentric passage 69 leading from the inner end of said chamber into communication with gasoline intake port 39. A by-pass pipe 68' leads from chamber 68 (full lines in Fig. 1 and broken lines in Fig. 2) back to the gasoline

supply tank. A valve seat 70 is provided at the juncture of passage 69 with chamber 68. A valve plug 71 has a body portion 71' mounted for axial reciprocation in passage 69 and an annular flange portion 71'' at the outer end of body portion 71' for engagement with seat 70 when the valve is pressed inward to close said passage. The body portion 71' of valve plug 71 is provided with longitudinal peripheral grooves 72 to establish communication between passage 69 and chamber 68 when valve plug 71 is in open position. Spring means 73 to urge valve plug 71 into closed position includes a stuffing box 74 secured removably to boss 67 in closing relation to chamber 68 by suitable means, such as bolts 75. Stuffing box 74 has a cylindrical chamber 76 equal in diameter to boss chamber 68 and disposed in alignment therewith. A piston-like packing gland 77 is mounted for reciprocation in chamber 76 of stuffing box 74 and has peripheral packing rings 78 to prevent fluid leakage around packing gland 77. An adjusting screw 79 journaled in the end wall of stuffing box 74 for external engagement by a wrench or other turning implement (not shown) has screwthreaded engagement with packing gland 77. A coil spring 80 fitted in an annular recess 81 in the inner end of packing gland 77 presses a pointed bearing head 82 against the indented outer end of valve plug 71. Adjusting screw 79 serves to permit manual adjustment of the tension of spring 80, whereby the pressure at which valve plug 71 may be opened by the gel stream may be predetermined to safeguard the homogenizer against the destructive effect of sudden stoppage of gel discharge through valve 54. Vapor lock is also prevented.

Upper end wall member 33 has a chambered boss 83 identical in construction with boss 67 though smaller in size. The interior of boss 83 has a by-pass pipe 84 connecting the same with the source of napalm supply (not shown). Relief valve means 85 identical with that constituted by parts 69-70-71 for the gasoline intake port is associated with napalm intake port 46. Adjustable spring means 86 to maintain valve means 85 closed under safe napalm pressure feed conditions, which is identical with the corresponding spring means associated with valve means 69-70-71, is located in boss 83 and is protected against fluid leakage by stuffing box means 87 identical with stuffing box means 73. When the pressure in the napalm supply line becomes dangerously high upon sudden closure of gel discharge valve 54, relief valve means 85 will vent the napalm intake port 46 into by-pass pipe 84.

Referring now to Figs. 8, 9 and 10, the operation of the device will be recounted.

Fig. 8 represents by solid line 88 the spiralling course of the flow of gasoline from intake port 39 upward with increasing pitch of its helix to region 89 which coincides with the location of gel discharge port 53 (Fig. 3). Broken line 90 represents the course of napalm from region 91, which coincides with the location of intake port 46 (Fig. 2), down through passage 42 to region 92, which coincides with the location of injection orifices 47-52, and thence upward in colloidal dispersion with the gasoline to region 89.

In Fig. 9, lines 93 represent the centrifugal or outward development of the motion of particles of napalm in the spiralling stream of gasoline, represented by line 94, in the region of injection of the former into the latter. The vacuum created in region 95, known as the "vortex tube,"

exerts a vaporizing effect on the napalm particles and lends impetus to the colloidal dispersion process.

Fig. 10 represents in a somewhat different graphical manner the successive stages of flow and homogenization action. For example, X designates the zone in which vortical motion is initially imparted to the entering gasoline stream by impeller 36; Y indicates the zone in which maximum circular velocity is imparted to the gasoline stream by the baffle units 48 of lowest pitch and in which napalm injection occurs; and Z designates the zone in which the flow of gel is decelerated in circular velocity and simultaneously accelerated in axial velocity to meet the required conditions of discharge from the homogenizer into the supply line leading to the gun breech.

It will be understood that it is intended to cover all changes and modifications of the examples of the invention herein chosen for the purpose of illustration which do not constitute departures from the spirit and scope of the invention.

Having thus described the invention, I claim:

1. A non-rotary homogenizer for producing a colloidally dispersed stable combination of a dispersed phase ingredient and a continuous phase ingredient comprising: structural means providing a cylindrical vortex chamber having an intake port at one end to admit said continuous phase ingredient under externally applied pressure and a discharge port for the combined product at its opposite end, said structural means also providing an intake port for the dispersed phase ingredient not directly communicating with the vortex chamber; immobile spiral flow generating means located in a primary zone and connected with the intake port for the continuous phase ingredient to impart initial vortical motion to said ingredient under the influence of its pressure when admitted to the vortex chamber in a secondary zone and thereby generate a central vortex tube in the fluid stream; and injection means for said dispersed phase ingredient comprising a conduit leading from the intake port therefor into the center of the secondary zone in the vortex chamber and having minute orifices in this zone only which establish communication between said conduit and the vortex tube of the fluid stream, whereby vaporizing suction is exerted by said vortex tube upon the dispersed phase ingredient inside said injection conduit prior to issuance through the orifices thereof.

2. A non-rotary homogenizer for producing a colloidally dispersed stable combination of a dispersed phase ingredient and a continuous phase ingredient comprising: structural means providing a vortex chamber of elongated cylindrical form having an intake port for the continuous phase ingredient at one end and an intake port for the dispersed phase ingredient together with a discharge port for the combined product at the opposite end, said vortex chamber being composed of a primary zone adjacent to the intake port for the continuous phase ingredient, a secondary zone of relatively short extent adjoining said primary zone, and a longer tertiary zone extending from said secondary zone to the discharge port; immobile spiral flow generating means located in said primary zone to impart vortical motion to the stream of continuous phase ingredient when admitted through the intake

port therefor under externally applied pressure and under the influence of said pressure; injection means for the dispersed phase ingredient including tubular conducting passage means leading from the intake port for said ingredient centrally through the tertiary and secondary zones and terminating short of the primary zone in a closed end, said conducting passage means having radial orifices in the secondary zone to inject the dispersed phase ingredient into the vortex tube region of the stream of continuous phase ingredient; spiral flow generating means of low pitch provided in the secondary zone to increase the circular velocity of vortical flow in said zone; and spiral flow generating means of high pitch provided in the tertiary zone to decelerate the circular velocity of flow in said zone and to accelerate the axial velocity of flow toward the discharge port.

3. A non-rotary homogenizer as defined in claim 2, wherein the spiral flow generating means in the tertiary zone is graduated upward in pitch away from the secondary zone.

4. A non-rotary homogenizer as defined in claim 2, wherein the spiral flow generating means in the primary zone is a frusto-conical impeller having spiral peripheral grooves leading from the intake port for the continuous phase ingredient into the secondary zone.

5. A non-rotary homogenizer as defined in claim 2, wherein the spiral flow generating means in the secondary and tertiary zones is composed of a series of axially spaced annular baffle plates surrounding the tubular connecting passage means for the dispersed phase ingredient, each baffle plate being divided by radial slots into segmental deflecting portions having leading edges axially bent in the direction of flow.

6. A non-rotary homogenizer as defined in claim 5, wherein the slots in adjacent baffle plates are spirally staggered.

7. A non-rotary homogenizer as defined in claim 6, wherein the degree of stagger in the tertiary zone exceeds that in the secondary zone.

8. A non-rotary homogenizer as defined in claim 6, wherein the angle of incidence of the leading edges of the baffle plates in the tertiary zone exceeds that in the secondary zone.

9. A non-rotary homogenizer as defined in claim 1, wherein means is located in the secondary zone to increase the circular velocity of vortical flow of the fluid stream above that in the primary zone.

10. A non-rotary homogenizer as defined in claim 9, wherein means is provided in a tertiary zone between the secondary zone and the discharge port to reduce circular velocity and increase axial velocity of the fluid stream.

LEON JEAN GEERAERT.
